UNITED STATES PATENT OFFICE.

LEVI DAMASKA, OF CADILLAC, MICHIGAN.

HEATING STOVE.

1,418,431.

Specification of Letters Patent. Patented June 6, 1922.

Application filed March 10, 1921. Serial No. 451,328.

To all whom it may concern:

Be it known that I, LEVI DAMASKA, a citizen of the United States, residing at Cadillac, in the county of Wexford and State of Michigan, have invented certain new and useful Improvements in Heating Stoves, of which the following is a specification.

This invention relates to improvements in heating stoves and has as its primary object to provide an attachment which may be arranged within the flue opening of any ordinary heating stove and which will serve to retard the passage of heated air currents and products of combustion from the stove to the flue so that a considerable portion of the heat which is ordinarily dissipated in passing up through the flue, is conserved by the aid of the invention.

Another object of the invention is to so construct the attachment that the heated air currents and products of combustion will be prevented from passing directly upwardly through the flue and will be caused, on the other hand, to take a path which will cause them to sweep in close proximity to the walls of the stove before passing out through the flue so that maximum benefit will be derived from the heat units radiated from the same.

In the accompanying drawing:

Figure 1 is a view partly in section and partly in elevation illustrating an ordinary heating stove equipped with the attachment, the latter being shown in vertical section;

Figure 2 is a detail side elevation of the attachment removed from the stove;

Figure 3 is a horizontal sectional view taken substantially on the line 3—3 of Figure 2 looking in the direction indicated by the arrows.

In the drawing, the numeral 1 indicates the body of a heating stove of an ordinary type, the numeral 2 the top of the body, and the numeral 3 the usual flue opening which is surrounded by the upstanding flange 4 over which is fitted the intake end of the flue or stove pipe 5. In this type of stove, the heated air currents and products of combustion ordinarily pass directly upwardly through the flue 5 without being retarded in their course, and as a consequence a considerable portion of the heat is dissipated in the flue and in the atmosphere when the gases leave the chimney, and it is to conserve this heat or a considerable portion thereof

at least, that the present invention is designed.

The device embodying the invention comprises a thimble which is indicated in general by the numeral 6 and which is of a shape and suitable dimensions to adapt it to be fitted down through the opening 3 and be snugly surrounded by the flange 4. The thimble or body 6 may be made of sheet metal or any other material suitable for the purpose and the same is provided exteriorly with a flange 7 which circumscribes its upper edge, this flange being adapted to rest upon the upper edge of the flange 4, when the device is in place, in the manner clearly shown in Figure 1 of the drawing, so that the thimble is supported in place in the opening 3 and in proper alignment with the flue 5. The thimble 6 is open at its upper end and unobstructed interiorly from its upper to its lower end except that at its lower end it is partly closed by a baffle plate which is indicated by the numeral 8 and which is preferably of a marginal contour the same as the cross sectional contour of the thimble. Also the plate 8 is preferably of marginal dimensions not greater than the exterior dimensions of the body of the thimble so that when the flue 5 is disconnected from the stove, the device as a whole may be fitted downwardly through the opening 3 to assume the position shown in Figure 1. The diametrically opposite sides of the thimble 6 are cut away, as indicated by the numeral 9, so as to provide draft passages or openings 10 located above the opposite sides of the plate 8 and also so as to provide oppositely located depending supporting members 11 located between the openings 10 and 95 having their lower end portions turned inwardly or flanged as at 12 and riveted or otherwise secured as at 13, to the upper face of the plate 8.

It will now be evident that the baffle plate 8 is located a distance below the plane of the top 2 of the stove body so that heated air currents and products of combustion rising from the burning fuel will be deflected in all directions laterally by coming in contact with the under side of this plate and thus be caused to pass in close proximity to the side walls of the stove body. The heated air currents and products of combustion will then sweep beneath the top 2 of the stove and will finally be deflected downwardly and about the thimble 6 and will

pass out through the openings 10 and up through the thimble and finally through the flue 5. Being thus retarded in their passage from the stove through the flue however, the 5 heated air currents and products of combustion will transfer the major portion of their heat units to the walls and top of the stove body so that full benefit is obtained of these units which would otherwise be lost.

10 Having thus described the invention, what is claimed as new is:—

A device of the class described comprising a thimble having a circumferential wall provided exteriorly at its upper end with a 15 circumscribing flange projecting in an outward direction to seat upon the wall of the flue opening of a stove, the said wall at the lower end of the thimble being cut away at

diametrically opposite sides to provide lateral passages and intervening depending 20 supporting portions, the lower ends of the said portions being bent inwardly toward each other and lying wholly within the bounds of said circumferential wall of the thimble, and a baffle plate secured to the 25 under side of the said inturned lower ends of the supporting portions with its margin substantially flush with the outer surfaces of said portions and lying wholly within the bounds of said wall whereby the thimble 30 may be bodily inserted in a downward direction into the flue opening of a stove and supported by said flange and may be bodily removed by upward displacement.

In testimony whereof I affix my signature. 35

LEVI DAMASKA. [L. s.]
